Primary Examiner — Cathron Brooks*Assistant Examiner* — Aula Soroush(74) Attorney, Agent, or Firm — Stetina Brunda Garred and Brucker(57) CLAIM

The ornamental design for a sports bra, as shown and described.

DESCRIPTION

FIG. 1 is a front elevation view of a sports bra showing my new design with the dotted lines depicting a user of the sports bra forming no part of the claimed design and with the dotted lines on the band and straps of the sports bra illustrating stitching;

FIG. 2 is a rear elevational view thereof;

FIG. 3 is a top plan view thereof;

FIG. 4 is a left side view thereof; and,

FIG. 5 is a bottom plan view thereof.

1 Claim, 2 Drawing Sheets(56)
